[57] CLAIM

The ornamental design for a stand-alone drive for disk-shaped data storage media, as shown and described.

DESCRIPTION

FIG. 1 is a front isometric view of a stand-alone drive for disk-shaped data storage media according to the present invention;

FIG. 2 is a top view of the drive shown in FIG. 1;
FIG. 3 is a bottom view of the drive shown in FIG. 1;
FIG. 4 is a front view of the drive shown in FIG. 1;
FIG. 5 is a rear view of the drive shown in FIG. 1; and,
FIG. 6 is a side view of the drive shown in FIG. 1 the opposite side view is identical.

Those portions of the drive shown in broken lines are included for illustrative purposes only and form no part of the claimed design.
